UNITED STATES PATENT OFFICE.

KARL ZENTNER, OF FRANKFORT-ON-THE-MAIN, GERMANY.

APPARATUS FOR KNEADING AND FORMING AMALGAMS.

Application filed December 29, 1926, Serial No. 157,854, and in Germany December 31, 1925.

The invention relates to an improved apparatus for mixing and preparing amalgams, more especially for use as dental fillings, and has for its object to provide a simple and effective mechanism, which will serve as a means for measuring the ingredients or constituents of the amalgam and also as a mortar in which the ingredients are worked and kneaded to the desired consistency and the excess mercury expelled, after which the body or pellet of amalgam is discharged ready for use. To this end, the invention comprises a mortar consisting of an upper and lower section connected together for independent rotation, each section being provided with a longitudinal bore traversed by a rod threaded on its lower end and engaging the threaded bore of the lower section and provided on its upper end with a piston-like head which fits the bore of the upper section and constitutes the bottom of the mortar as well as the element for discharging the finished body or pellet of amalgam ready for use.

The invention is illustrated in the accompanying drawings, in which:—

Fig. 1 is a sectional elevation through the apparatus.

Fig. 2 is a plan view thereof.

Fig. 3 is a side elevation of the stylus or pestle, which may be conveniently employed with the mortar.

Referring to Fig. 1, the mortar comprises a base section a^1 provided with a longitudinal bore, the lower part of which is internally screw threaded and the upper portion of which is enlarged to form a socket to receive the reduced cylindrical end of the upper member a , which latter is also provided with a longitudinal bore of two diameters in the upper and larger section of which operates a piston e formed upon a rod f traversing the smaller portion of the bore and provided at its lower end with a screw threaded section g , which engages the threaded portion of the bore of the lower section a^1 .

The sections a and a^1 are secured together to prevent relative longitudinal movement and to permit independent rotation of the sections by means of a set screw c tapped into an opening in the upper portion of the section a^1 , the end of the pin engaging a circumferential groove in the reduced portion b of the upper section a . By this particular coordination, it will be apparent that, if the parts a and a^1 are turned in opposite direc-

tions, the piston e will be displaced or moved up or down within the cylindrical bore of the upper section a .

Associated with the mortar is a special form of pestle comprising a cylindrical body portion h having a headed end i adapted to knead the ingredients of the amalgam contained within the space l above the piston e . The opposite end of the pestle is provided with a cylindrical section k adapted to fit the bore above the piston and to serve as a means for compressing the amalgam to express the excess mercury and reduce the amalgam to the form of a cylindrical pellet.

In using the apparatus, the piston e is so adjusted in the upper portion of the section a , by rotating the sections a and a^1 with respect to each other, as to provide a space sufficient to receive the necessary quantity of metal filings and mercury to make up the required amount of amalgam. This hollow space above the piston e is filled with the amalgam mass which is kneaded with the headed end i of the pestle until the mass has acquired the proper plasticity or consistency. The mass is then compressed with the cylindrical end k of the pestle to express any excess of mercury and reduce the mass of the amalgam to cylindrical form, which is then discharged from the hollow space by further rotating the parts a and a^1 to raise the piston until the pellet of amalgam is discharged from the bore. By this relatively simple apparatus, the desired amount of amalgam may be quickly and accurately prepared without the operator being required to handle the ingredients and knead the mixture in his hands as has been customary, thereby avoiding the danger of impairing the health of the operator from mercurial poisoning.

Preferably the upper end of the section a is dished or concaved toward the bore to facilitate the charging of the metal filings and the mercury into the bore.

What I claim is:

1. An apparatus for forming amalgams, comprising a container having a cylindrical bore and a piston adjustably fixed within said bore to regulate the cubical content of the bore and serve as a means for discharging the finished amalgam from the bore.

2. An apparatus for forming amalgams, comprising an upper section and a lower section connected for independent rotation and provided with aligning longitudinal

bores, and a piston fitted in the bore of the upper section and having a stem in threaded engagement with the bore of the lower section, whereby relative rotation of the sections will effect longitudinal adjustment of the piston within the bore of the upper section.

3. An apparatus for forming amalgams, comprising an upper member having a longitudinal bore, a lower member having a telescopic engagement with the upper member, means for locking the members together against longitudinal motion but permitting

independent rotatory motion of the respective members, and a piston fitted in the bore of the upper member and having a rod provided with threads on its lower end engaging the threads in the bore of the lower member, whereby rotation of the upper and lower members in opposite directions will move the piston in the bore of the upper member to regulate the cubical capacity of the bore above the piston, and also to discharge the finished amalgam from the bore.

In testimony whereof I affix my signature.
KARL ZENTNER.
